UNITED STATES PATENT OFFICE.

EPHRAIM DRENSSTEIN, OF NEW YORK, N. Y.

ARCH-SUPPORTER.

1,135,100.

Specification of Letters Patent. Patented Apr. 13, 1915.

Application filed November 11, 1913. Serial No. 800,298.

To all whom it may concern:

Be it known that I, EPHRAIM DRENSSTEIN, of the borough of Brooklyn, county of Kings, city and State of New York, have 5 invented certain new and useful Improvements in Arch-Supporters, of which the following is a specification.

My invention relates to that class of arch supporters made principally of metal which 10 are designed to fit each individual foot.

The object of this invention is to provide an arch supporter which can easily be made to fit the foot of the wearer and which is laterally adjustable.

15 A further object is the provision of an arch supporter whose supporting parts can readily be pressed from sheet metal and which with slight alterations can be adjusted to the individual foot.

20 I attain these objects by the construction shown in the accompanying drawings, in which,

25 Figure 1 is a plan view of one form of my invention and Fig. 2 is a vertical section of the same on the line A—A of Fig. 1.

My improved arch supporter is divided longitudinally into two or more supporting parts as 1 and 2, (Fig. 1) which are made preferably of metal and which may be 30 finished off by leather or other suitable covering if desired in a manner well known to the art and which forms no part of my invention. Said supporting parts are each shaped to fit and support a certain part of 35 the entire supported portion of the foot and are fastened together by any suitable fastening means such as rivets, or are adjustably fastened together by the nuts 11 on screws 10. The adjustability of my sup- 40 porter to various sizes laterally is obtained by means of slots as 9 in either of the supporting parts in this case supporting part 2, or in both parts, in which the fastening means as screws 10 and nuts 11 slide. An- 45 other way of obtaining the lateral adjust- ment is by overlapping the supporting parts as 1 and 2, Fig. 1, the required amount and then riveting said parts together.

By making the supporter of several parts 50 longitudinally, said parts as 1 and 2 may be readily fashioned in a suitable press and then made to fit the individual foot accurately and exactly by slight alterations if needed.

55 For additional strength at the place where it is most needed, reinforcing strips

may be used, said strips running the entire length of the supporter or only part of the length as desired. When no reinforcing strips are used, the bottom of the supporter 60 is primarily dependent for its rigidity on the overlapping of members 1 and 2. It is obvious that more than one thickness of reinforcing material may be used or a series of narrow strips may be substituted for the 65 long strip shown without departing from the spirit of my invention. The longitudinal members 1 and 2, may be adjusted to the required width and then riveted or otherwise fastened to the reinforcing strip or 70 strips.

I do not limit myself to the specific construction shown as it is obvious that certain changes can be made without departing from the scope of my invention, such 75 as the use of fastening means other than rivets or the screws and nuts shown.

What I claim is:

1. An arch supporter comprising solid 80 permanently formed overlapping metallic members substantially of the same length along their overlapping edges, each of said members being shaped to fit and support one side and part of the bottom of the individual foot to be supported, said mem- 85 bers being arranged for lateral adjustment, and means for longitudinally securing said members in their adjusted position, the bottom of said supporter being primarily de- 90 pending for its rigidity on the overlapping of said members.

2. An arch supporter comprising solid 95 permanently formed uniformly overlapping metallic members substantially of the same length along their overlapping edges, each of said members being shaped to fit and support one side and part of the bottom of the individual foot to be supported, said members being arranged for lateral adjust- 100 ment, the overlapping edges of said mem- bers remaining substantially parallel during and after adjustment, and means for longitudinally securing said members in their adjusted position.

3. An arch supporter comprising solid 105 permanently formed uniformly overlapping metallic members substantially of the same length along their overlapping edges, each of said members being shaped to fit and support one side and part of the bottom 110 of the individual foot to be supported, said members being arranged for lateral adjust-

ment, the overlapping edges of said members remaining substantially parallel during and after adjustment, and means for longitudinally securing said members in their adjusted position, the bottom of said supporter being primarily dependent for its rigidity on said overlapping.

Signed this 10th day of November, 1913,
in the presence of two subscribing witnesses.

EPHRAIM DRENSHTEIN.
